(57) **CLAIM**

The ornamental design for a cosmetic product, as shown and described.

DESCRIPTION

FIG. 1 is a top perspective view of a cosmetic product, embodying the new design;

FIG. 2 is a bottom perspective view of the design shown in FIG. 1;

FIG. 3 is a front view of the design shown in FIG. 1;

FIG. 4 is a back view of the design shown in FIG. 1;

FIG. 5 is a right-side view of the design shown in FIG. 1;

FIG. 6 is a left-side view of the design shown in FIG. 1;

FIG. 7 is a top view of the design shown in FIG. 1; and

FIG. 8 is a bottom view of the design shown in FIG. 1.

FIG. 9 is a top perspective view of a second embodiment of a cosmetic product, embodying the new design;

FIG. 10 is a bottom perspective view of the design shown in FIG. 9;

FIG. 11 is a front view of the design shown in FIG. 9;

FIG. 12 is a back view of the design shown in FIG. 9;

FIG. 13 is a right-side view of the design shown in FIG. 9;

FIG. 14 is a left-side view of the design shown in FIG. 9;

FIG. 15 is a top view of the design shown in FIG. 9; and,

FIG. 16 is a bottom view of the design shown in FIG. 9.

The broken lines shown in the figures are for illustrative purposes only and form no part of the claimed design.
